UNITED STATES PATENT OFFICE.

WILLIAM J. RITCHHEY, OF PITTSBURG, PENNSYLVANIA.

SPRING-LOCK FOR HATCHWAYS.

SPECIFICATION forming part of Letters Patent No. 310,320, dated January 6, 1885.

Application filed December 2, 1884. (No model.)

To all whom it may concern:

Be it known that I, WILLIAM J. RITCHHEY, a citizen of the United States, residing at Pittsburgh, in the county of Allegheny and State 5 of Pennsylvania, have invented certain new and useful Improvements in Spring-Locks for Hatchways and other Doors, of which the following is a full, clear, and exact description, reference being had to the accompanying drawings, forming part of this specification, in which—

Figure 1 is a bottom plan view of a pair of partially-open hatchway-doors with my improved locking device attached. Fig. 2 is a 15 sectional view of the same on line $x-x$ of Fig. 1. Fig. 3 is a sectional view showing the doors closed and held in place by the locking device. Fig. 4 is a detail to be referred to.

My invention relates to improved means for 20 automatically securing hatchway and other doors; and it consists in the peculiar arrangement, construction, and combination of devices, all of which I shall hereinafter fully describe and claim.

25 To enable others skilled in the art to make and use my invention, I will now proceed to describe the exact manner in which I have carried it out.

Heretofore great difficulty and serious accidents have been occasioned by the failure 30 in keeping hatchway-doors closed after they have been operated upon by a cam or similar devices generally employed in closing said doors. To overcome these difficulties, and at 35 the same time provide a cheap and substantial locking device, and one that can be applied to any hatchway, is the object of my invention.

Referring to the said drawings, A and A' 40 represent a pair of sliding hatchway-doors of ordinary construction. The upper and lower inner corners of each of these doors are cut away, as at a and a' , as shown in Fig. 1.

Bolted to the under surface of the door A, 45 and in line with its outer edges, are the metallic plates B, their free ends being bent outward at right angles, to furnish bearings for the anti-friction rollers C, which assist in the sliding movement of the doors.

50 At suitable points between the plates B are bolted or otherwise secured the metallic spring

plates or catches D, each having a curved end, and provided with a loop or bend, d , adapted to engage a projection on the opposite door, as will be hereinafter more fully described. 55

The door A' is similar in construction to the door A, and it is provided with metal plates E, which are bolted to the door, and formed in a manner similar to those on the door A. It will be noticed that the plates E are secured 60 at points inside the edges of the door A', and preferably on a line with the inner surface of the cut-away portions a' , so that when the doors are closed the anti-friction rollers F, which are journaled in the plates in a manner similar to the rollers C, enter the cut-away portions of door A, while the rollers C perform a like function in the door A'. The metal plates E are provided with inwardly-projecting studs H, constructed and arranged so that when the 65 doors are closed the spring-catches D come in contact with the studs, and, springing over the same, securely hold the doors in a closed condition, as shown in Fig. 3. The construction of the springs and their relation to the 70 studs can also be used with advantage for other purposes, such as shown in Fig. 4, where the spring-lock is applied to a box or other receptacle, to which it may be applied and used with good effect. When thus used, a pin, I, 75 passing through an opening in the box, presses against the spring and disengages it from the stud and allows the box to be opened. 80

Having thus described my invention, what I claim as new, and desire to secure by Letters 85 Patent, is—

The door A, having metallic plates B, the outer ends of which are bent at right angles to receive the journals of the anti-friction rollers C, and spring-catches D, formed with a 90 bend or loop, d , in combination with the door A, provided with angular plates E, in which are journaled anti-friction rollers F, and inwardly-projecting studs H, secured to the plates F, and adapted to engage the catches 95 on the opposite door, all constructed and combined to operate as herein set forth.

WILLIAM J. RITCHHEY.
